CLAIM

The ornamental design for a lamp, as shown and described.

DESCRIPTION

- 1.1 is a top, front, and right side perspective view of a lamp showing my new design;
 1.2 is a right side elevation view thereof;
 1.3 is a left side elevation view thereof;
 1.4 is a front elevation view thereof;
 1.5 is a rear elevation view thereof;
 1.6 is a top plan view thereof; and
 1.7 is a bottom plan view thereof.
